C. A. Adams

INVENTOR

John J. Jacobs;
BY Charles Turner Brown,
ATTORNEY

UNITED STATES PATENT OFFICE.

JOHN J. JACOBS, OF CHICAGO, ILLINOIS.

ELASTIC LINK.

No. 926,655.

Specification of Letters Patent.

Patented June 29, 1909.

Application filed April 4, 1908. Serial No. 425 34.

To all whom it may concern:

Be it known that I, JOHN J. JACOBS, a resident of Chicago, in the county of Cook and State of Illinois, and a citizen of the United States, have invented certain new and useful Improvements in Elastic Links, of which the following, when taken in connection with the drawing accompanying and forming a part hereof, is a full and complete description, sufficient to enable those skilled in the art to which it pertains to understand, make, and use the same.

This invention relates to attachments applied to suspenders, belts, and other articles of wearing apparel.

The object of the invention is to obtain an attachment made of metal, preferably of sheet metal, which may be used on suspenders to attach the button ends thereof to the webbing which covers or passes over the shoulders of the wearer, and which will obviate the necessity of using elastic webbing, and which may be used in belts, and for other purposes.

A further object of the invention is to obtain an attachment of the kind named which, in addition to being so constructed that the yielding or elastic character thereof will permit its use as an elastic member, will be slightly in appearance, economically made, and not liable to get out of order, and durable.

In the drawing referred to, Figure 1 is a front elevation of a device embodying the invention. Fig. 2 is a side elevation of a device embodying the invention, showing one end of the front of a suspender attached thereto. Fig. 3 is a top plan, or end view, of a device embodying this invention. Fig. 4 is a perspective view of one of the elements of the device. Fig. 5 is a perspective view of a rod or roller used as an element in the device. Fig. 6 is a modification of the spring forming an element in the device. Fig. 7 is an additional modification of the spring forming an element in the device; and Fig. 8 is a plan view of a blank from which the sheet metal portion of the device is formed or bent up.

A reference letter applied to designate a given part is used to indicate such part throughout the several figures of the drawing, wherever the same appears.

A, (Fig. 8), is a blank cut or stamped out from sheet metal. a, a, are broken lines on which the blank A is bent to form a channel in which the U or inverted U-shaped piece B

may move. a' and a'' are broken lines on which, also, the blank A is bent to set the part a''' of the blank out so that the webbing of the suspenders, (lettered H), may be passed underneath such part a'''. D, D, are apertures or holes in blank A, through which, after the blank is formed upon the broken lines a, a', and a'', a pin or bar (E), is passed and secured, as by riveting, or heading. The wires or bars E may have a shoulder thereon, and also the roller F, (as is shown in Fig. 5), if preferred. A bar or rod E is also secured in the inverted U-shaped movable piece B, and this bar or rod may also have a roller thereon, if preferred. G is a spring, inserted in the channels formed by the bends a, a, of blank A, so that the upper end of the spring abuts against the upper one of the rods or bars E, and also against the movable inverted U-shaped piece B, yieldingly holding such piece B near to the lower one of the bars or rods E in the frame obtained by bending up the blank A.

G', Fig. 6 and G'', Fig. 7, are, respectively, modifications of the spring G, and may be substituted therefor.

H is the webbing of a suspender, (or of a belt or other like article), and I is the ordinary adjusting device on suspender webbing.

The several parts or elements of the device are assembled as follows: After the blank A is cut out and formed up the lower bar or pin E is put in place and headed; and then the inverted U-shaped piece B, (with a wire E headed therein) is put in the channels of the device, a spring G, (previously formed up) is placed in the channels and on the U-shaped piece B, and an additional pin or rod or bar E is put in place in the remaining holes D, D, in the sheet metal part of the device and riveted or headed.

To use the device the webbing H is put through the aperture h between the pin or bar E and the part a''' of the device, and through the aperture h'. The webbing is then brought up and fastened, as by the adjusting device I.

J, J', are ends of a suspender which are provided with button holes, and such ends are passed through the aperture h', to rest on the lower one of the bars or rods E. When thus arranged any strain on the buttoned ends and sustained by the upper end of the webbing H will be received on the spring, which will be compressed thereby. An elastic loop is thus obtained which may be used

on suspenders, and belts, and other articles: and when such elastic loop is used the webbing or belting need not be elastic.

It is evident that the bars E, E, may be secured in place by solder, in the frame formed by the blank A, in the construction illustrated, or by any other suitable means, instead of by the insertion of the ends of such bars in holes D, D; that the upper bar E receives the thrust of the spring G; and that the lower bar E serves as the means for the attachment of ends J, J', or their equivalent, to the device.

Having thus described my invention and the construction of a device embodying the same, what I claim as new and desire to secure by Letters Patent is,

1. A frame provided with channels, bars attached to the frame at the ends thereof to close the ends of the channels, the portion of the frame between the channels and adjacent to one of the end bars arranged to permit webbing to be passed between the frame and the end bar, a bar parallel to the end bars and arranged to move in the channels, and a spring interposed between the movable bar and the end bar at one end of the frame, the bends of the spring arranged to fit and move in the channels, such movable bar and the remaining end bar severally arranged to permit webbing to pass over them; substantially as described.

2. An elastic loop comprising a frame provided with channels, means to close one of the ends of the channels, a spring provided with bends and with straight portions between the bends, such bends arranged to move in the channels and the channels ar-

ranged to guide and retain the spring in operative form, a webbing arranged to pass between the frame and the spring, and operatively connected to said spring, such spring arranged so that one end thereof abuts against the means whereby the ends of the channels are closed, and the other end thereof yieldsingly holds the webbing.

3. The combination of a frame provided with parallel channels, means to close such channels at one end of the frame, and means at the other end of the frame to attach the frame to an article, a spring in the channels, the spring arranged so that one end thereof abuts against the means whereby the ends of the channels are closed at one end of the frame and the other end thereof is movable, and means to attach the movable end of the spring to an article; substantially as described.

4. The combination of a frame provided with parallel channels and provided with a connecting plate arranged to stand out from and in a plane in front of the plane in which the channels lie, with means to close the ends of the channel at one end of the frame, a spring in the channels arranged so that one end thereof is movable and the other end thereof abuts against the means whereby the ends of the channels are closed, means to attach an article to the frame and means to attach an article to the movable end of the spring; substantially as described.

JOHN J. JACOBS.

In the presence of—

CHARLES TURNER BROWN,
CORA A. ADAMS.
